UNITED STATES PATENT OFFICE.

OLE MINSAAS, OF TACOMA, WASHINGTON.

COMBINED SAW SET AND JOINTER.

1,164,842.

Specification of Letters Patent. Patented Dec. 21, 1915.

Application filed May 6, 1915. Serial No. 26,355.

To all whom it may concern:

Be it known that I, OLE MINSAAS, a resident of the United States, residing at Tacoma, in the county of Pierce and State 5 of Washington, have invented certain new and useful Improvements in Combined Saw Sets and Jointers; and I do declare the following to be a full, clear, and exact description of the invention, such as will enable 10 others skilled in the art to which it appertains to make and use the same.

My invention is a combined saw set and jointer and has for its object to provide such a tool which although being very simple in construction, will possess a number of 15 advantageous features and will be therefore highly efficient in operation, the numerous features of construction employed in reducing the invention to an operative device being hereinafter fully described and particularly pointed out in the claims.

In describing the invention, I shall refer to the accompanying drawings wherein like reference characters designate corresponding 20 parts throughout the various views and wherein:

Figure 1 is a side elevation of a tool constructed in accordance with my invention showing the position of parts when used as 25 a jointer; Figs. 2 and 3 are respectively top and bottom views of the tool when used as a jointer; Fig. 4 is a central vertical longitudinal section with the parts disposed for use as above set forth; Fig. 5 is a vertical 30 transverse section as seen along the plane indicated by the line 5—5 of Fig. 1; Fig. 6 is a top plan view of the tool assembled for use as a saw set, and Fig. 7 is a central vertical longitudinal section of the tool when 35 used for this purpose.

In these drawings, constituting a part of the application, the numeral 1 designates a head which includes a yoke 2 having a rounded front end 3, while its rear end 4 lies substantially at right angles to its arms. Projecting laterally from the yoke 2, and in the present application shown as depending therefrom, is a rigid jaw plate 5 which spans the gap between the two arms of the 45 yoke and whose inner edge is integrally secured to said arms. Extending from the aforesaid inner edge of the rigid jaw plate 5 to the rounded end 3 of the yoke and likewise spanning the aforesaid gap, is a plate 50 6 which is formed integrally with the jaw 55

5, the arms of the yoke and the end 3 thereof, said plate having an opening 7 which is disposed approximately at its center and adapted for the reception of a screw to be described.

Lying parallel with the jaw plate 5 and movable toward and away therefrom, is a movable jaw plate 8 having a pair of ears on its outer side through which the laterally bent ends 9 of a U-shaped lever 10 are passed, the arms 11 of this lever 10 being bent into the form of U's lying in planes at right angles to the lever proper. At suitable points between their ends, the arms 11 are inserted behind ears 12 on the rear corners 60 of the yoke 2 and are pivoted at these points by screws 13 or the like. The looped end of the lever 10 lies contiguous to the side of the yoke remote from the jaw plate 5 and is at this point disposed in contact with an 65 adjusting screw 14 threaded through the curved end 3 of said yoke, whereby proper manipulation of said screw will move the jaw plate 8 toward or away from the plate 5 as the case may be, thus varying the width 70 of the space between the two plates 5 and 8, it being evident that this space constitutes 75 a guide-way to receive the saw S.

The inner side of the previously mentioned guide-way communicates with an additional guide-way 15 which is likewise disposed transversely of the head 1, this guide-way 15 being provided for the reception of a file 16 which thereby forms an inner wall 80 for the saw guide-way. By this construction and arrangement of parts, it will be evident that when the jaw plates 5 and 8 are disposed in contact with the opposite sides of the saw and the teeth thereof project against the file 16, the entire tool may 85 be moved longitudinally upon the saw, thus causing the file to true the teeth of said saw, this truing being commonly termed jointing. During this operation, were some efficient means not provided to retain the file 90 16 within the guide-way 15, it would undoubtedly be moved therefrom. Since the tool is to be used not only as a jointer, but as a saw set, and since such a set must be equipped with a plunger, it becomes highly 100 expedient to so dispose this plunger as to allow the same to serve not only as a setting member, but as means to clamp the file in active position. To this end, the rear end 105 4 of the yoke 2 is provided with a depending 110

lug 17 having an opening 18 which communicates with the guide-way 15 and which slidably supports a plunger 19 which, when the file is in use, bears against the same as 5 clearly disclosed in Fig. 4, when the movable handle 20 which is pivotally connected to said plunger is moved toward the rigid handle 21 which is formed integrally with the yoke 2. When the jointing operation 10 has been completed, it is simply necessary to allow the handle 20 to recede from the handle 21 to a certain extent, whereupon the file 16 will be released and may be easily removed.

15 A poly-sided anvil 22 having bevels of various angles on its several faces, is now disposed within the yoke 2 and in contact with the plate 6. When the anvil is in this position, a threaded central opening 20 with which it is formed aligns with the opening 7 and receives the threaded end of a screw 23 which is disposed upwardly through said opening 7. It will thus be seen that by proper manipulation of the 25 screw 23, any of the faces of the anvil 22 may be disposed toward the plunger 19. The result is, that when this plunger is projected upon the teeth of the saw inserted between the jaw plates 5 and 8, such teeth 30 will be bent laterally or set in the well known manner. (See Fig. 7). During the setting operation, it is important that the jaw plates 5 and 8 be disposed in close contact with the saw, thus preventing the latter 35 and the tool from moving in respect to each other while the several teeth are being set. By so doing, much better results are obtained.

From the foregoing description, taken in 40 connection with the accompanying drawings, it will be evident that although an extremely simple construction has been provided for carrying out the object of the invention, such construction is very unique 45 and highly efficient in operation, possessing a number of very advantageous features. Particular emphasis is laid upon the fact that the plunger 19 performs the twofold function of a file clamp and a tooth setting 50 member, upon the construction of the lever 10 and its connection with the plate 8, and upon the general construction of the head, it being essential that construction be provided whereby the anvil 22 is surrounded 55 by the yoke, thus preventing it from being injured by rough usage. The most noticeable advantages gained by the construction of the lever 10 and the movable jaw plate 8, is that the two arms of said lever may 60 yield to a certain extent to allow the tool to be adjusted longitudinally upon the saw, and that the pivotal connections between the plate 8 and said lever allow the former to readily adjust itself into proper contact 65 with the saw.

In the foregoing, I have described certain specific details for producing probably the best results, and in the accompanying illustration have shown such details. It will be evident, however, that I need not be limited thereto otherwise than to the extent to which 70 the following claims limit me.

I claim:

1. A tool comprising a head having therein a guide-way for the reception of a saw, 75 and an additional guide-way adjacent the aforesaid guide-way and adapted to receive a file, combined with saw setting means operable in conjunction with the first-named guide-way.

2. A tool comprising a head having therein a guide-way for the reception of a saw, and an additional guide-way communicating 80 with the first-named guide-way and adapted to receive a file, combined with saw setting means operable in conjunction with the first-named guide-way.

3. A tool comprising a head having therein a guide-way for the reception of a saw, and an additional guide-way communicating 85 with the first-named guide-way and adapted to receive a file, combined with a plunger movable into the additional guide-way and constituting a combined saw setting and file clamping member.

4. A tool comprising a yoke having a rigid jaw plate extending longitudinally from one of its sides and spanning the gap between its arms, a plate extending from the inner edge of the jaw plate to one end 90 of the yoke and likewise spanning the aforesaid gap, a plunger operable into the yoke through the opposite end thereof, and an additional jaw plate disposed parallel to the aforesaid jaw plate.

5. A tool comprising a head, a fixed jaw member carried thereby, a lever fulcrumed between its ends to said head, a movable jaw member adjacent the fixed jaw member and having a pivotal connection with one end of 100 said lever, and an adjusting screw actuating in conjunction with the opposite end of the latter to adjust the movable jaw member toward and away from the fixed member.

6. A tool comprising a head, a fixed jaw member carried thereby, a U-shaped lever having its arms bent into the form of U's lying in planes at right angles to the plane in which the lever proper is disposed, fulcrums carried by the head and passing 110 through the aforesaid arms of the lever, a movable jaw member adjacent the fixed jaw member and having pivotal connections with the free ends of said arms and an adjusting screw actuating in conjunction with the looped end of said lever to adjust the movable jaw member toward and away from the fixed member.

7. A tool comprising a head having thereon a fixed jaw member, a movable jaw mem-

ber adjacent said fixed member, a yielding lever fulcrumed to the head and connected to the movable member, and means to vary the resiliency of the aforesaid lever, where-
5 by to project the movable member toward the fixed member with greater or less force.

8. A tool comprising a head having thereon a fixed jaw member, a movable jaw member adjacent the fixed member, and spring

means normally forcing the movable mem- 10
ber toward the fixed member.

In testimony whereof I have hereunto set my hand in presence of two subscribing wit-
nesses.

OLE MINSAAS.
